WILBUR F. BUDLONG, OF BEREAL, OHIO.

VISE OR CHUCK OR LIKE MACHINE.

1,017,846.

Specification of Letters Patent.

Patented Feb. 20, 1912.

Application filed March 20, 1911. Serial No. 615,708.

To all whom it may concern:

Be it known that I, WILBUR F. BUDLONG, citizen of the United States, residing at Berea, in the county of Cuyahoga and State of Ohio, have invented certain new and useful Improvements in Vises or Chucks or Like Machines, of which the following is a specification.

This invention relates to improvements in 10 a vise or chuck or like machines, and the invention consists in the construction substantially as shown and described and particularly pointed out in the claims.

In the accompanying drawings, Figure 1 15 is a plan view of the invention and Fig. 2 is a side elevation thereof showing the clamping jaws in working relation. Fig. 3 is a longitudinal sectional elevation showing the clamping jaws separated with the loose 20 jaw retired. Fig. 4 is a front elevation as seen in Fig. 3. Fig. 5 is a cross section on a line corresponding substantially to α - α , Fig. 3 and designed particularly to show a cross section of the base upon which the 25 other parts are mounted. Fig. 6 is a detail showing the connection of the link with the screw head and adapted to be operated by lever L. Fig. 7 shows two views of the height and width gage arranged at the side 30 of the machine.

The invention as thus shown represents a vise or chuck designed for use for all purposes where vises or chucks are used in machine work, and is adapted to combine with 35 the adjustable jig features for the duplication of parts to be built on the interchangeable system. With slight change in form or of the form of the bed piece the device may be built for use on either drilling machine, 40 milling machine, lathe, turret lathe, planer or shaper or other machines. As a whole the machine is designed to permit the quick and accurate placing of work to be operated upon, to securely hold each successive piece 45 in the same relative position, to accurately guide the operating tool in its work and to quickly and freely release the work when completed from the vise or chuck jaws and from all guides, stops and bushings. Having 50 these objects and operations in view the machine has a bed piece or base B provided with a fixed jaw B', and opposite this on said base is the loose or slidable jaw C which has guide ribs 2 on its bottom running in 55 longitudinal slots 3 in bed B and confined beneath by plates 4 lengthwise and screws

5. The said jaw C is moved back and forth by means of the lever L as a handle and which also serves to tighten the work in the machine. Thus, the said lever has rounded 60 bearing portions 6 between which the end of connecting link E is pivoted on transverse pin 7. Said pin is set eccentrically in said rounded bearings so that as the said lever is depressed it will operate with a drawing and 65 clamping effect upon the said link and thus operate to bind the parts together as presently seen. The higher part of the eccentric or cam portions of said rounded bearings is opposite from the handle of the lever so 70 that the movement of the lever L to a vertical position has the effect of releasing the tension on the connecting link E while the depression of the lever accentuates the tension. Said lever is pivotally connected with 75 the head 8 of screw S. The said bearings 6 impinge against the rear rounded projection c of the slidable jaw C and operate to press said jaw inward by reason of the pull on link E by lever L. This occurs because the 80 screw S is held at the front by nuts N and N' bearing against stop P which is lowered over the screw in its notch or open slot 10 and bears against the nose 12 of the jaw to take the rearward pull on the screw. The 85 said stop P is supported on a rod R running lengthwise beneath in the bottom of bed B and having a controlling handle H at its rear end by which said rod is axially rotated and stop P thrown in or out. The 90 stop is out in Figs. 3 and 4 and in Figs. 1 and 2, and the open slot 10 is adapted to seat closely over the adjusting screw S so as to take all pressure.

In operation work W is placed between 95 the jaws B' and C, which, by reason of the conforming facings or plates M on said jaws and the guide O is brought into its proper position. Then as the lever L is raised to a vertical position the jaw C is pushed forward firmly against the work and the nut N and lock nut N' adjusted close against stop P and then the depression of lever L by reason of its eccentricities causes the loose jaw to be pressed in firmly against the work. 100 Locking of the work depends therefore at least on these last agencies. Nut N' serves to lock nut N, and these nuts with stop P can at the most only engage the parts together in a close but not in a clamped relation, but when adjusted and when the lever L is pulled down toward the horizontal po- 110

sition to make effective its eccentric action in its bearings 6 the work is securely locked within the jaws. On the other hand the work is released by simply raising the lever 5 L to a vertical position, which releases the extreme tension caused by the eccentric action of the lever and permits easy separation. The stop P is then thrown back by means of the lever H and this permits the 10 drawing of the loose jaw and screw S rearward and which carries the nuts N and N' back beneath base B, Fig. 3. Pulling the lever L backward performs this withdrawal together with the withdrawal of jaw C to 15 the fullest extent, the stop lug c', Fig. 3, being placed the proper distance back in the base to accomplish this end. This lug also serves as a guide and support for screw S. The fulcrum head 8 for screw S moves in a 20 planed way between the bottom ribs b' of the base and which guide it in its travel. Pins 7 and 14 connect link E with lever L and screw head 8 respectively.

For the duplication or a continuous run 25 of work of the same size and kind the jaws B and C are provided with removable facings M secured to same by screws, pins or other devices. The said facings are cast, machined or ground to conform to a portion 30 of the surface of the piece or work to be operated upon and in such a manner as to permit the accurate and uniform placing of the piece or successive pieces. The piece or work is then "laid off" and placed in the 35 vise or chuck in the manner hereinbefore described and the same securely locked. In this connection I employ combination height and width gages having stepped rests or supports O, which are arranged at the sides 40 of the machine and secured in position by means of slotted arms 17 and supporting rods 18. The tool T is then brought into correct position for operation and the jaws of the vise or chuck are secured in corresponding 45 position against the work. The tool is then raised from the work and the adjustable arms A for guiding the same are mounted on pivots 20 on the fixed jaw in this instance but may be mounted on the 50 movable jaw, and hardened steel bushings or guides 22 are secured by screws, bolts or other means in said arms for said tool or tools. The said hardened steel guides are interchangeable and may be made in any 55 suitable form for the guidance of the particular tool in use, such as round for boring and tapping, rectangular for slotting and planing and other shapes for eccentric form. The graduated height and width guides or 60 gages O are reversible on the rods 18, giving a wide range of height and width for work. They are adjustable sidewise or laterally by means of the rods 18 and lengthwise on the slotted arms 17, which are engaged at the 65 side of jaw B' by screws 19.

By means of stop P to throw against the front of the base B I obtain a fixed clamping abutment for nut N and at the same time I can throw said stop back when a slight release of the parts occurs and thus 70 be able to open jaw C to the fullest extent and not be troubled with nuts or the like to effect such movement and without altering the position of nuts N, N', thus adapting the machine to use on the same size of stock or 75 work indefinitely. A piece of work W is shown in Figs. 1 and 2.

B² represents a cross bar which connects the ends of the bars A therewith by means of bolts b² and both said cross-bar and said arms are slotted for engagement by said bolts and adapted to rigidly fix said arms to said bar when the proper adjustment has been effected.

A spring 15 is mounted upon pin 14 and 85 engaged with link E and head 8 to constantly maintain the fixed angular relations shown, particularly when sliding adjustments are being made.

What I claim is:

1. A vise or like machine having a slidably mounted jaw, means to fix the working position of said jaw comprising a screw and nut, a lever with an eccentric bearing adapted to tighten the parts when otherwise adjusted and locked, and a link pivotally uniting said screw and lever.

2. A vise or like machine having a suitable base provided with a fixed jaw and having a slot therein, a slidable jaw, a non-rotatable screw slidably mounted within said base and having a screw-nut thereon, a device removably interposed between said nut and the base and adapted to limit the lengthwise movement of said screw, a link 100 connected with said screw and extending through said slot, and a lever having an eccentric bearing adapted to draw said link and slidable jaw to clamp the work between the jaws after the preliminary adjustment 105 of said parts has been effected.

3. A vise or like machine having one fixed and one movable jaw, in combination with means adapted to set said jaws to engage work of a given size and to clamp the jaws 115 on the work without changing positions of the adjustable parts, the said means comprising an eccentrically mounted operating lever, a downwardly-inclined link pivotally united with said lever, a jaw-adjusting 120 screw connected with said link, a nut on said screw, and a notched stop to engage said nut.

4. In vises and the like, a fixed jaw, a 125 slidable jaw and a screw and eccentric-operating-lever therefor mounted to move therewith, a nut adjustably mounted on said screw, and a stop for said nut movably mounted and adapted to be thrown into and out of engagement therewith.

5. A vise or the like having a fixed jaw 130

and an adjustable jaw, in combination with removable facings for said jaws having irregular outlines conforming to the work, gages for the work supported at the side 5 thereof and adapted to enter between said jaws, adjustable tool supports mounted on the top of one of said jaws and arranged to work between said side gages, and an adjustable cross-bar to unite said tool supports.

6. A vise or like machine having clamping jaws and a transversely-adjustable width gage having stepped rests for the work adjustably mounted at the side of the 15 machine between the said clamping jaws, in combination with a guide for the work tool between said jaws.

7. A vise having a pair of clamping jaws, slotted arms adjustably mounted at the side 20 of the vise and height and width adjusting means supported at the side of the machine by said arms and adapted to enter between said jaws, said means comprising stepped supports for the work having stems adjustably fixed in said arms.

8. A vise or like machine having a movable and a fixed jaw and a tightening mechanism for the movable jaw comprising a

screw and a nut thereon, a pivoted stop at one end of the machine adapted to form a 30 bearing for said nut against the body of the machine, a rod extending lengthwise through the machine supporting said stop and adapted to be rotated to throw the pawl into and out of working position, and a lever 35 connected to the movable jaw so that said jaw is moved by swinging the lever and connections between said lever and said screw.

9. In a vise or like machine, a base and a movable and a fixed jaw thereon, in combination with means to clamp said jaws on work comprising a screw, a lever, and a link connected to said screw eccentrically connected with said lever, an adjustable nut on said screw and a pawl pivoted to swing into 45 working position between said base and said nut, whereby when said parts are brought operatively together said lever can be depressed and said parts clamped on the work.

In testimony whereof I affix my signature in presence of two witnesses.

WILBUR F. BUDLONG.
